UNITED STATES PATENT OFFICE.

HENRY HERBERT YELF, OF SOUTHSEA, PORTSMOUTH, ENGLAND.

COMBINATION DEVICE FOR TYPE-WRITERS.

1,012,786.

Specification of Letters Patent. Patented Dec. 26, 1911.

Application filed July 18, 1910. Serial No. 572,585.

To all whom it may concern:

Be it known that I, HENRY HERBERT YELF, a subject of the King of Great Britain, residing at 43 Pelham road, Southsea, Portsmouth, in the county of Hampshire, England, have invented a certain new and useful Combination Device for Type-Writers, of which the following is a specification.

10 The present invention relates to a combination device for typewriters and one object of the invention is to provide an easily attachable and detachable accessory device which is cheap to manufacture and which 15 will serve as a receptacle for refuse such as that of rubber, eraser, and paper, such refuse being occasioned by the act of erasing erroneous characters or words from type-written productions while in the machine, another 20 object being to adapt such a device for use as a hand rest, eraser holder, pencil holder, locking device, protector and advertisement or sign plate, without appreciably increasing the cost as will be hereinafter 25 particularly described.

According to this invention a receptacle is formed from sheet metal, wood veneer, papier mâché, celluloid or other suitable material and is so constructed that it may be 30 quickly inserted into position in such relation to the platen, that when erasing takes place the particles of rubber or eraser and paper fall down into the receptacle which thus prevents the said particles from falling 35 into or on to pivots, or bearings or other delicate or vital parts of the typewriter.

As is well known particles of ink eraser as commonly used at the present day contain such matters as are capable of inflicting 40 injury even upon bearings of a hard nature, and the use of the device according to the invention not only makes for cleanliness but actually prolongs the life of the machine and allows the accuracy of the fitting of parts of the latter to be preserved 45 for a much greater length of time.

In the application of simple means the device can be made to serve as a hand rest, eraser holder, pencil holder and so on and 50 can be made silent and harmless to the polished wood of tables or the like upon which it may be deposited when not in use, all as will be hereinafter particularly described with reference to the drawings and pointed out in the appended claims.

In the accompanying drawings forming part of this specification:—Figure 1 is a perspective view of a novel device according to this invention as seen from the front; Fig. 2 is a perspective view looking into the interior 60 of the receptacle from the rear; Fig. 3 is a rear elevation; Fig. 4 is a cross section of a typewriting machine of the so-called front-strike variety, showing my device in operative position thereon, and Fig. 5 is a perspective view as seen from the front of a portion of a machine to which the novel device is applicable.

As is well known the modern tendency is to construct machines on the front-strike 70 principle according to which the type *a* on the type bars *b* or levers lie normally near to the keyboard *c*, diagrammatically indicated in Fig. 4 and which when operated, are thrown upwardly and rearwardly 75 against the platen *d*. Reference to Fig. 5 will show that the type-carrying levers *b*, are arranged in these machines so as to lie approximately in the surface of a semi-cylinder or other segment of a cylinder and 80 Fig. 4 illustrates the manner in which the pivots *e* of the levers are located immediately beneath the front portion of the periphery of the platen *d* so that when an erasure is made upon the paper sheet *f* 85 by rubbing the latter where supported by the platen, the particles of eraser and paper fall down directly upon the pivots *e* and other delicate and important parts located immediately beneath. In order to catch 90 and receive all such refuse particles and the like the invention provides a receptacle comprising a body portion *g* which is suitably bent to follow somewhat the curvature of the grille surface formed by the assemblage 95 of type bars or levers *b* and closed at one end by a segmental end plate *h* soldered riveted or otherwise suitably fixed to the body portion *g*. The curved edge of the plate *h* preferably extends beyond the under 100 surface of the portion *g* and preferably closely follows the curve of the grille constituted by the levers *b*. Near to the opposite end of the body portion *g* there may be a shallow upstanding flange *j*, which acts as a stop 105 as hereinafter described and which may be cut away as at *k* to allow of fitting flush against the framing in spite of projections upon the latter. The end plate *h* may have its upper edge *l* curled or bent over so as to 110

constitute a pencil-holding device and also to offer a smooth harmless and convenient support upon which to rest the hand or wrist when erasing and on its surface toward the interior the plate *h* may be fitted with a loop, or pocket, or clip *r* for supporting and retaining a circular or other eraser *s*. The longitudinal edges of the body portion *g* are conveniently bent over as at *m* for the purpose of engaging the uppermost side type levers of the curved series and the bent over parts *m* may be horizontal at and near the open end of the body portion *g* these horizontal portions merging into downwardly inclined portions at and near the end plate *h*. The curved edge of the plate *h* may be shod with rubber as for instance by securing peripherally thereto a rubber strip. In the drawings a rubber strip *n*, is secured over a portion of the periphery by fixing the two ends of the strip in clips *o* and providing a flange or seating *p* for the rubber strip *n* to lie along so as just to protrude beyond the periphery of the plate *h*.

The device is applicable for use as follows:—When an erasure is to be made the receptacle is inserted into the machine so that its open end enters the space between a segmental portion *g* of the framing and the assemblage of type bars *b*. The receptacle is pushed in until the flange *j* comes flush with the framing part *g* and the periphery of the end plate *h* stands upon the assemblage of type bars *b*. The particles which fall during the act of erasing are caught in the receptacle *g* and prevented from falling on to the operative parts. The curled edge *l* is situated at just a convenient height for the hand or wrist to be supported thereupon so that it is possible to apply just the requisite pressure which is not easy to do if the hand or wrist is not supported. It is to be noted that when in position in the machine the side flanges *m* take over the uppermost type bars and are supported thereby. When the erasure is finished the receptacle is removed and the debris may be emptied therefrom.

50. When the device is laid upon a polished table the rubber *n* prevents the edge of the plate *h* from scratching the polish and to this end the edge of the open end of the body *g* may be similarly fitted.

55. When the typewriting machine is not in use the receptacle can be inserted in position, as seen in Fig. 4, wherein it will not only protect the parts which it covers from dust but will also prevent the keys if accidentally knocked from throwing up the type bars and spoiling any work which may be left in the machine.

What I claim and desire to secure by Letters Patent of the United States is:—

65. 1. In a typewriting machine, the combination with the machine-frame and the type-basket, of a refuse receiver comprising an open-top receptacle provided with supporting means arranged to engage fixed parts of the machine to hold the receptacle within the type-basket and below the plane of the platen.

2. In a typewriting machine, the combination with the machine frame and the type-basket, of a refuse receiver comprising a hollow receptacle open at the top and provided at its edges with supporting flanges to engage a fixed part of the machine for holding the receptacle within the type-basket below the plane of the platen. 70

3. A refuse receptacle for a typewriting machine comprising a hollow body or vessel, a downwardly extending edge on the front wall of said vessel, said edge being adapted to stand upon the type bars of a front strike 75 machine, said body or vessel being adapted to fit into said machine so as to stand in receptive position with relation to the platen. 80

4. A combination fitting for a typewriting machine comprising a receptacle, a downwardly extended edge on the front wall of said receptacle said edge being adapted to stand upon the type bars of a front strike machine, said body or vessel being adapted to fit into said machine so as to stand in receptive position with relation to the platen. 85

5. A refuse receptacle for typewriting machines comprising a bent sheet body a front wall downwardly extended to form a foot for said receptacle, a bent over upward extension on said wall adapted to serve as a hand rest, and an upstanding flange or wall 95 in said receptacle adapted to serve as a stop device substantially as set forth. 90

6. A refuse receptacle for typewriting machines comprising a bent sheet body, a front wall therefor, a downward extension thereon serving as a foot therefor, clips on said extension, a seating on said extension and a rubber guard secured in said clips and fitting on said seating so as to constitute a shoe for said foot, said receptacle being 105 adapted to fit into said machine so as to stand in receptive position with relation to the platen substantially as set forth. 100

7. A refuse receptacle for typewriting machines comprising a bent sheet body, a front wall for said vessel, a foot at the front end of said vessel, a rubber shoe, and means adapted to secure said shoe to said foot. 110

8. A refuse receptacle for typewriting machines comprising a bent sheet body, a front wall for said vessel a foot at the front end of said vessel said foot having a contour corresponding approximately with the contour of the grille formed by the assemblage of type bars, and side flanges on the longitudinal 115 120 125 130

hal edges of said body said flanges being adapted to take on to the uppermost side members of said assemblage.

9. A combination fitting for typewriting machines comprising a receptacle crescent shaped in transverse section, a downwardly extended portion on the front wall of said receptacle said extension forming a crescent shaped foot, and flanges along the longitudinal edges of said receptacle substantially as and for the purposes set forth.

10. A combination fitting for typewriting machines comprising a receptacle crescent shaped in transverse section, a downwardly extended portion on the front wall of said receptacle said extension forming a crescent shaped foot, an upstanding transverse flange in said receptacle said flange being situated at a little distance from the rear end of said receptacle, a rubber shoe fitted around the periphery of said foot, means for securing said shoe in position and flanges along the longitudinal edges of said receptacle substantially as and for the purpose set forth.

11. A combination fitting for typewriting machines comprising a receptacle crescent

shaped in transverse section, a downwardly extended portion on the front wall of said receptacle said extension forming a crescent shaped foot, an upstanding transverse flange in said receptacle said flange being situated at a little distance from the rear end of said receptacle, a rubber shoe fitted around the periphery of said foot, means for securing said shoe in position and flanges along the longitudinal edges of said receptacle substantially as and for the purpose set forth.

12. A combination fitting for typewriting machines comprising an open receptacle, a foot on the front end of said receptacle, a hand rest supported on said front end, and flanges on the longitudinal edges of said receptacle.

In testimony whereof I affix my signature in presence of two witnesses.

HENRY HERBERT YELF.
